JAMES BIRRELL AND WILLIAM BIRRELL, OF SEATTLE, WASHINGTON, ASSIGNEES, BY
MESNE ASSIGNMENTS, TO WATER VACUUM CLEANER CO. INC.

INDUCED SUCTION FOR VACUUM-CLEANERS.

1,023,359.

Specification of Letters Patent. Patented Apr. 16, 1912.

Application filed May 8, 1911. Serial No. 625,805.

To all whom it may concern:

Be it known that we, JAMES BIRRELL and WILLIAM BIRRELL, citizens of the United States, residing at Seattle, in the county of 5 King and State of Washington, have invented certain new and useful Improvements in Induced Suction for Vacuum-Cleaners, of which the following is a specification.

10 This invention relates to vacuum cleaning apparatus and, more particularly, to devices for effecting the flow of dust laden air from a dust collecting nozzle through a discharge pipe.

15 The object of the present invention is the provision of a device associated with the dust discharge pipe and arranged to be detachably connected to a faucet of a house water-system affording water pressure sufficient to induce a flow of air to create the requisite suction.

A further object is the adaptation of the device so that the dust-laden air when drawn into a suitable chamber will subject 25 the dust to the water for saturation thereby causing the produced heavy matter to free itself from the air, so that the latter finally escapes in a practically purified state.

30 The invention is illustrated in the accompanying drawing which is a vertical section of the same applied to a water-faucet.

The reference numeral 1 represents a water-faucet provided with a threaded bib 2, as ordinarily. 3 is an internally threaded socket which is screwed upon said bib. Extending downwardly from such socket is a water discharge nozzle 4 which projects into a suction-chamber 5. This chamber is made 40 of a substantially conoidal shape and has at its bottom a discharge opening 6 extending through a nozzle 7 which, in turn, projects downwardly into what we designate as the mixing-chamber 8. This chamber is also 45 of a conoidal shape and has a discharge opening 9 at the bottom through a tubular extension 10. The axes of the aforesaid chambers, nozzles and the extension 10 are in vertical alinement with the axis of the faucet bib.

An air inlet 11 is provided for the referred to suction-chamber 5 and is disposed with its axis at or about the elevation of the bottom of the water-nozzle 4. Said air inlet extends through a nipple 12 provided in 55 the wall structure of the casing for the various chambers. The nipple 12 is screw threaded to receive the coupling 13 for a flexible pipe 14 which is connected with a dust collecting funnel which may be of ordinary or suitable design.

The operation of the invention is as follows: When the water-faucet is opened a stream of water is discharged at a high velocity through water-nozzle 4 to create a 65 partial vacuum in the suction-chamber 5 thereby inducing a flow of dust-laden air into the suction-chamber and which is ejected with the water into the mixing chamber 8 wherein the mixing of the dust particles 70 and water is completed and the air liberated from the dust. In the mixing chamber the various fluids effervesce with considerable violence. In discharging from the mixing chamber the purified air returns to the 75 room, while the combined dust and water is discharged to a sink or hopper whence it escapes through a drain pipe to a sewer.

What we claim, is—

In a device of the class described, a casing having an air inlet at one side and a water inlet at the top terminating in a nozzle depending into the chamber of the casing, the casing at its lower end terminating in a discharge nozzle, and a second casing integral at its upper end with the first-mentioned casing and terminating at its lower end in a discharge nozzle, the nozzle depending from the first-mentioned casing extending into the chamber of the second- 90 mentioned casing, all of said nozzles being in direct vertical alinement with the axis of the chambers, and the side inlet of the first-mentioned casing being in a plane with the discharge nozzle of the water inlet. 95

JAMES BIRRELL.
WILLIAM BIRRELL.
